PROPELLER ADJUSTING MECHANISM

George F. Wislicenus, Millburn, N. J., assignor to
Worthington Pump and Machinery Corporation, Harrison, N. J., a corporation of Delaware

Application July 23, 1942, Serial No. 452,025

5 Claims. (Cl. 170—163)

This invention relates to propellers or runners for axial flow pumps or turbines, to propellers for aeroplanes and ships and the like, and more particularly to such propellers or runners having adjustable vanes or blades.

An object of the present invention is the provision of an adjustable blade propeller for use in axial flow pumps for the purpose of controlling the head capacity curves of such pumps and to permit variations in operating conditions at a constant speed of rotation, avoiding undue head and power rise under low or reduced flow conditions.

Another object of the present invention is to provide an adjustable vane propeller or runner for turbines as employed in the Kaplan turbine, resulting in a broadening of the efficiency curve of the turbine under varying operating conditions.

The invention may further be utilized in the construction of propellers for aeroplanes where it is desired to adjust the pitch of the propeller to compensate for varying operating conditions, as for take-off versus regular flight or diving conditions, and various altitudes.

The present invention provides a propeller more efficient and practical than the known type of such adjustable blade propellers since its construction is such as to negate backlash. Links, cams and similar elements having clearance and giving rise to mechanical wear are eliminated. The invention further enables the building of a compact, accurately adjustable propeller mechanism, positive in action and with a minimum of moving parts required to translate the axial movement of the actuating mechanism into the rotary movement necessary for adjusting the position of the vanes or blades.

With these and other objects in view, as may appear from the accompanying specification, the invention consists of various features of construction and combination of parts, which will be first described in connection with the accompanying drawings, showing a propeller adjusting mechanism of the preferred form embodying the invention, and the features forming the invention will be specifically pointed out in the claims.

In the drawings

Figure 1 is a longitudinal section through the hub of a propeller constructed in accordance with the present invention.

Figure 2 is a cross-section through the hub taken on the line 2—2 of Figure 1.

Figure 3 is a view of the hub shown in Figure 55 1 from the left side, with the shaft section "A" removed.

Figure 4 is a view of the hub shown in Figure 1 from the right side, with the cap "B" removed.

Figure 5 is a diagrammatic illustration of the method of operation of the present invention.

5 Referring more particularly to the drawings, the propeller or runner illustrated comprises a hollow hub body 1 having a plurality of blades 2 extending radially therefrom. The blades 2 are of any approved form, designed according to 10 conditions under which the propeller or turbine is to operate, for giving the most efficient performance. The blades 2 are so attached to the hub body 1 as to allow limited rotary movement with respect to said hub body for the purpose of 15 changing or adjusting their angle in relation to and to affect the flow of the medium in which the propeller or runner is being rotated.

The blades 2 are formed upon a circular base portion 3, which latter seats in a bearing surface 4 formed in the hub body 1. A cylindrical extension 5 extends inwardly toward the axis of the hub body 1 from the base 3 of the blade 2. The extension 5 has a reduced portion 6 at its innermost end which cooperates with a bearing surface 7 formed in a bearing ring 8. The latter is rigidly attached to the hollow hub body 1 by means of the bolts 9.

20 A drum 10 is firmly attached to and for rotation with the cylindrical extension 5 just inwardly of the base 3 of the blades 2, and has bearing surfaces 11 and 12 formed thereon cooperating with bearing surfaces 13 and 14 respectively formed in the hub body 1 to provide a fulcrum for rotative adjusting movement of the blades 2, and to take up the awkward pull of the vanes due to centrifugal forces as well as other forces acting on the vanes.

25 A flexible tensioned member 15, either a wire rope, steel tape or the like, is wrapped around the drum 10 and has its ends attached to spiders 40 16 and 17, respectively. The tensioned member 15 is prevented from sliding on the drum 10 by shaping the drum in a suitable manner as shown at 18, or by suitable clamps or other means. Such 45 means, however, are not essential since the friction will generally prevent the flexible tensioned member 15 from sliding on the drum 10.

The tensioned member 15 is held tensioned by means of the two spiders (between the two spiders) 16 and 17. The spiders 16 and 17 are fastened upon an axial stem 19, movable longitudinally of the axis of the hub body 1 and extending through an axial bore in the propelling shaft A. This stem 19 may be moved longitudinally by any means (not shown) exteriorly of the hub 1 and shaft A for controlling the adjustment of the blades 2.

The spider 16 is rigidly attached to the stem 19 for longitudinal movement therewith and is located in a chamber 20 formed in the hub body 1. Openings 21 are formed in the spider 16 for receiving the ends 25 of the flexible member 15.

The spider 17 is also attached to the stem 19 toward its outer end, and is spaced from the spider 16 by a tubular spacing ring 22 formed about the stem 19. This spider 17 is attached to the stem 19 by means of a threaded sleeve member 23 threaded into the spider body 17 and having an annular ring 24 on its innermost end which contacts the tubular spacer 22. By adjusting this threaded member 23 the spider 17 may be moved upon the stem 19 with relation to the spider 16 for adjusting the tension of all of the flexible members 15 in unison, which members 15 are attached at their opposite ends 25 and 26 to the two spiders 16 and 17 respectively.

By moving the stem 19 longitudinally of the axis of the hub 1, the two spiders 16 and 17 will be moved simultaneously, and consequently the flexible members 15 will also be moved. The members 15, being wrapped about the drums 10, will, upon such movement, rotate the drums and consequently rotate the blades 2, the direction of which rotation being governed by the axial direction in which the stem 19 is moved.

Individual adjustment or tightening of the flexible members 15 may be obtained by means of the threaded connections 27 by which the members 15 are attached at their ends 25 to the spider 16, compensating for stretching, etc., of the members 15. Also, such individual adjustment of the tensioned members permits adjustments of the individual vanes, one by one, within small limits. Bolts 28 are employed for holding the bearing ring 8, the hub body 1, and shaft A in a fixed relative position.

It will be understood that the invention is not to be limited to the specific construction or arrangement of parts shown, but that they may be widely modified within the invention defined by the claims.

What is claimed is:

1. In a propeller pitch adjusting mechanism, a propelling shaft, a hollow hub member attached to said propelling shaft, a plurality of blades extending radially from and rotatably carried by said hub, an extension on the inner end of each of said blades and extending into and toward the axis of said hub, a drum fixed on each of said extensions, a tensioned member wrapped about each of said drums, moveable means carried by said hub, said tensioned members connected to said moveable means and moveable upon movement of said moveable means to impart rotary movement to said drums to vary the pitch of the propeller blades, means for individually adjusting the tension of said tensioned members, and means for adjusting the tension of all of said tensioned members in unison.

2. In a propeller, a propelling shaft, a hollow hub member attached to said shaft, a plurality of propeller blades extending radially from and rotatably carried by said hub member, an extension on the inner end of each of said rotatable blades and extending toward the axis of said hub, a drum on each of said extensions and rotatable therewith, tensioned members wrapped about each of said drums, a stem centrally located within said hub and moveable axially of the hub, spiders fixed upon said stem on oppo-

site sides of said drums, means for adjusting the axial positions of said spiders upon said stem with relation to each other for varying the tension upon said tensioned members, said tensioned members being attached to said spiders and so constructed and arranged that the tensioned members will be moved in unison with the stem to rotate said drums.

3. In a propeller, a propelling shaft, a hollow hub member attached to said shaft, a plurality of propeller blades extending radially from and rotatably carried by said hub member, an extension on the inner end of each of said rotatable blades and extending toward the axis of said hub, a drum on each of said extensions and rotatable therewith, tensioned members wrapped about each of said drums, a stem centrally located within said hub and moveable axially of the hub, spiders fixed upon said stem on opposite sides of said drums, means for adjusting the axial positions of said spiders upon said stem with relation to each other for increasing the tension upon said tensioned members, means at one end of each of said tensioned members for adjusting its connection to one of said spiders for varying the tension on each of said tensioned members individually, said tensioned members being attached to said spiders and so constructed and arranged that the tensioned members will be moved in unison with the stem and spiders to rotate said drums.

4. In a propeller pitch adjusting mechanism, a drive shaft, a hollow hub member carried by and rotatable with said shaft, a plurality of propeller blades carried by said hub member and mounted to rotate in unison with the hub member about the axis of the shaft and to rotate independently of the hub member about their own axes, a stem extending longitudinally into said hub and moveable relative to the hub, a pair of opposed spiders carried by said stem for unitary movement in the same direction, flexible members each having its ends connected to said spiders and being coiled intermediate its ends about one of said blade extensions whereby the propeller blades will be rotated about its own axis upon movement of the spiders, and means adjustably connecting one of said spiders to said stem for adjusting the tension of all of said flexible members in unison.

5. In a propeller pitch adjusting mechanism, a drive shaft, a hollow hub member carried by and rotatable with said shaft, a plurality of propeller blades carried by said hub member and mounted to rotate in unison with the hub member about the axis of the shaft and to rotate independently of the hub member about their own axes, a stem extending longitudinally into said hub and moveable relative to the hub, a pair of opposed spiders carried by said stem for unitary movement in the same direction, flexible members each having its ends connected to said spiders and being coiled intermediate its ends about one of said blade extensions whereby the propeller blades will be rotated about its own axis upon movement of the spiders, means adjustably connecting one of said spiders to said stem for adjusting the tension of all of said flexible members in unison, and means adjustably connecting the ends of said tension members to the other spider for permitting individual adjustment of the tension of the flexible members.
